PROTECTOR CLIP FOR USE IN HAIR
WAVING OPERATIONSErnest O. Frederics, New York, N. Y., assignor to
E. Frederics, Inc., New York, N. Y., a corpo-
ration of New York

Application December 1, 1928. Serial No. 323,057

14 Claims. (Cl. 132—36.1)

This invention relates to devices serving to clamp the hair and protect the scalp during hair waving operations, and to correlated inventions and discoveries appertaining thereto.

5 In general, it is the object of the invention to provide a device of the character described which will efficiently accomplish the purposes for which it is intended, which may be readily and economically manufactured and assembled, 10 and which may be manipulated with extreme ease.

Another object of the invention is to provide a protector clip which will hold the hair taut while the same is wound upon a curler and 15 while it is undergoing treatment.

Another object of the invention is to provide a protector clip which will substantially eliminate any possibility of injury to the scalp of the subject during a hair waving operation.

20 Other objects of the invention will in part be obvious and will in part appear hereinafter.

The invention accordingly comprises an article of manufacture possessing the features, properties, and the relation of elements which will be 25 exemplified in the article hereinafter described and the scope of the application of which will be indicated in the claims.

For a fuller understanding of the nature and objects of the invention, reference should be had 30 to the following detailed description taken in connection with the accompanying drawing in which:

Figure 1 is a perspective view of the protector clip embodying the invention and illustrates the same in open position;

Fig. 2 is a perspective view of the protector clip in closed position and with a curler mounted thereon;

Fig. 3 is a side view of the protector clip and 40 curler showing the same in operation;

Fig. 4 is a vertical section taken in the direction of the arrows along the lines 4—4 of Fig. 1 showing the tightening means in detail; and

Fig. 5 is a vertical section taken in the direction of the arrows along the lines 5—5 of Fig. 2 showing the protector clip with the curler omitted.

In permanent waving operations, and particularly in winding tresses of hair on a curling 50 device by the Croquignole method of winding, in which laterally spread tresses of hair are wound upon themselves on a curling device, it is desirable that the hair be held taut during the winding operation so as to be uniformly 55 spread and properly wound, and that the scalp

of the subject be securely protected against burning or other injury when heat is applied to the wound hair. Because of the many operations involved in waving a head of hair and because of the annoyance to which the subject is subjected by delays of the operator, it is also desirable that devices used in the waving operations be of such nature that they can be manipulated with the greatest possible ease.

In the exemplified embodiment of the invention there is accordingly provided a protector clip which will easily and securely clamp the hair, which will fully protect the scalp during operation, and which can be put in place, tightened and released with the utmost ease.

The particular clip exemplified comprises a pair of metallic arms 9 and 10 hingedly connected at 11 and having secured to the upper surface thereof supplemental members 12 and 13, respectively, serving to provide longitudinal channels 14 and 15 respectively in which are inserted cushion members 16 which may be composed of any suitable material, such as rubber. It is to be observed that the adjacent sides of the cushion members 16 are widened at 17 to 80 prevent the cushion members from being forced within the channels 14 and to provide an especially tight closure to protect the scalp of the subject. In order to facilitate its manipulation, the arm or block 10 is provided with a lug 18 85 having a corrugated outer edge 19. For the purpose of holding the arms together when the protector clip is in closed position with the cushion members 16 fitting over the tresses of hair, the arm 10 is provided with a lug or catch 20 90 and the arm or bar 9 is provided with a locking element 21 which is notched at 22 to receive the lug 20 and is pressed inwardly by a spring 23.

In operation, the tresses of hair to be waved are slipped between the cushion members, and 95 the arms 9 and 10 are pushed together, the locking element 21 automatically snapping over the lug 20. The tresses of hair are now held between the wide edges 17 of the cushion members 16 and are adapted to be wound on a curler, 100 such, for example, as the curler 24. In order to hold the curler 24 in place, there are provided on the arm 10 brackets 25 and 26 having forked ends 27 and 28 into which fit, respectively, the attaching block 29 and the stem 30 of the curler. 105 As exemplified, the forked end 28 cooperates with the attaching block 29 to resist rotation, whereas the curler is adapted to be rotated when desired in one direction by means of a knob 31. A type of curler well adapted for use in connection with 110

the present invention is exemplified in my co-pending application, Serial No. 311,994, filed October 12, 1928.

It is desirable that the arms of the clamp be drawn tightly together so as to press the cushions firmly against the hair, and to form an effective seal between the waving apparatus and the scalp of the subject. To this end, the locking element 21 extends through a slot 32 at the rear of the channel 14 and is provided at its end with a ring 33 having a circular recess. Extending through the ring and displaced from the center thereof toward the outer end of the locking element is a pin 34 on which there is mounted a lever 35 formed with a disc 36 fitted within the ring 33, so that when the lever is moved in a clockwise direction, the locking element 21 will be drawn inwardly to pull the arms of the clamp toward each other.

In order to effectively insulate the clamp and the heater held thereby from the scalp of the subject, a heat insulating strip 37 is secured in spaced relation to each of the arms 9 and 10, by means of pins 38, and a supplemental heat insulating strip 39 is secured in spaced relation to each of the strips 37 by means of pins 40. Thus the insulating properties of the strips are supplemented by the air spaces between the strips 37 and the arms, and between the strips 37 and 39, and any heat transfer by the connecting pins will be dissipated, so that danger of the transfer of a harmful amount of heat from the waving apparatus to the arms and thence to the scalp of the subject is eliminated.

It will thus be seen that a clamp is provided which is well adapted to hold the curling device, which can be put in place by one simple movement of the operator, which can be tightened by a second simple movement, and which is arranged to effectively protect the scalp of the subject.

Having described my invention, what I claim as new and desire to secure by Letters Patent is:

1. In a protector clip for use in hair waving operations, the combination of a pair of hinged-45ly connected arms, means to support a curling rod on one of said arms, cushion members having wide exposed surfaces adapted to be pressed against each other when the arms are moved into closed position, means automatically and 50 releasably to secure said arms in closed position, means associated with said securing means for drawing said arms closer together, and a plurality of spaced insulating strips secured to the underside of each of said arms.

2. In a protector clip for use in hair waving operations, the combination of a pair of hinged-60ly connected arms, a catch on one of said arms, a locking element on the other of said arms adapted to cooperate with said catch to hold the arms in closed position, a circular recess formed in said locking element, a disc fitting within said recess, means for pivotally mounting said locking element, said means including a pin positioned eccentrically of said disc and of said recess, and a lever secured to said disc and arranged to impart rotary movement thereto for drawing said arms together.

3. In a protector clip for use in hair waving operations, the combination of a pair of hinged-70ly connected arms, means including a locking element for releasably securing said arms one to the other, said locking element being formed with a recess, a disc fitting within said recess, a pivot pin positioned eccentrically of said disc,

and a lever arranged to impart rotary movement to said disc for drawing said arms together.

4. In a protector clip for use in hair waving operations, the combination of a pair of hinged-80ly connected arms, forked means to support a hair waving device on one of said arms, a cushion member on each of said arms adapted to be pressed against tresses of hair to clamp the same tightly when said arms are in closed position, means automatically and releasably to secure said arms in closed position, a lever associated with the last-mentioned means and arranged to draw said arms tightly against each other to increase the clamping action thereof, an insulating member secured in spaced relation to each of said arms, and a supplemental insulating member secured in spaced relation to each of the aforesaid insulating members.

5. In apparatus for use in hair waving operations, the combination with a curling rod equipped with an attaching element adapted for relative rotation with respect thereto, of a protector clip comprising a pair of hinged-95ly connected arms adapted to clamp tresses of hair therebetween, and a pair of supports carried on one of said arms, one of said supports being adapted rotatably to hold said curling rod and the other of said supports being adapted to hold said attaching element and to prevent the rotation of the same.

6. In apparatus for use in hair waving operations, the combination with a curling rod equipped with an attaching element adapted for relative rotation with respect thereto, of a protector clip comprising a pair of hinged-100ly connected arms adapted to clamp tresses of hair therebetween, a forked element for rotatably securing said curling rod from one end of one of said arms, and a forked element for supporting said attaching element from the other end of said one of said arms and for preventing the rotation thereof.

7. In a protector clip for use in hair waving operations, the combination of a pair of hinged-110ly-connected longitudinally-extending arms arranged to clamp therebetween longitudinally-extended series of strands of hair, means automatically and releasably to secure said arms in clamping position, and manually-operable cam means to draw said arms more tightly against each other to increase the clamping action thereof.

8. In a protector clip for use in hair waving operations, the combination of a pair of hinged-120ly-connected longitudinally-extending arms arranged to clamp therebetween longitudinally-extended series of strands of hair, means automatically and releasably to secure said arm in clamping position, and manually-operable cam means associated with said securing means to draw said arms more tightly against each other to increase the clamping action thereof.

9. In a protector clip for use in hair waving operations, the combination of a pair of hinged-130ly connected arms, one of said arms being formed with an opening at its free end, a spring-pressed pivoted locking bar on the free end of the other arm and adapted to extend through said opening when in closed position, and co-operating notch and catch means on said locking bar and at said opening to hold said arms in closed position.

10. In a hair waving device, in combination, a curling rod formed at one end with a flat-sided block and a protector clip comprising a 150

- pair of hingedly-connected arms adapted to clamp tresses of hair therebetween, a forked support at one end of one of said arms for receiving said flat-sided block and for preventing rotation thereof, and supporting means at the other end of said arms for receiving the other end of said rod. 5 portions of the gripping bar and the gripping block, and means for holding the spindle relative to the gripping block.
11. In a protector clip for use in hair waving operations, the combination of a pair of hingedly-connected arms, a curler-supporting bracket extending upwardly from each end of one of said arms directly above said arm, at least one of said brackets comprising a pair of prongs above said arm and adapted to receive therebetween a portion of a curling rod. 10 13. In a hair curling device in combination a curling rod and a protector clip comprising a pair of hingedly connected arms adapted to clamp tresses of hair therebetween, and means at the ends of said clip to support said rod in offset relationship to the line of clamping action of the arms. 80
12. A hair curling apparatus comprising an elongated gripping block, a gripping bar operatively associated with one side edge of the gripping block so that a lock of hair may be releasably clamped between the gripping bar and the side of the gripping block, a spindle detachably mounted longitudinally of the gripping block in offset relation in a vertical plane to the opposed 15 14. In a hair waving device, in combination, a curling rod formed at one end with a flat-sided block and a protector clip comprising a pair of hingedly-connected arms adapted to clamp tresses of hair therebetween, a forked support at one end of one of said arms for receiving said flat-sided block and for preventing rotation thereof, supporting means at the other end of said clip for receiving the other end of said rod, and cam means arranged to draw said arms 90 95 tightly together. 95
